UNITED STATES PATENT OFFICE.

GEORGE THOMAS MACFARLANE, OF PINNER, ENGLAND.

WINCH.

1,323,550.

Specification of Letters Patent.

Patented Dec. 2, 1919.

Application filed May 22, 1917. Serial No. 170,123.

To all whom it may concern:

Be it known that I, GEORGE THOMAS MACFARLANE, a subject of the King of Great Britain and Ireland, residing at Pinner, in the county of Middlesex, England, have invented Improvements in Winches, of which the following is a specification.

This invention relates to winches and has for object to provide a winch particularly suitable for use as a ship's winch for handling cargo quickly and without undue shock, "overhauling" of the winch barrel being effected rapidly and detrimental heating and wear of the brake devices being avoided.

In a winch according to the invention, the barrel, or each barrel, is freely mounted on the driving shaft and is rotated therefrom, through epicyclic gear controlled by brake drums furnished with band brakes and to prevent the barrel or to prevent each barrel, when rotating in a lowering direction, acquiring too high a speed under the action of gravity, and, to reduce the necessity for employing the brake, so much as would otherwise be the case the barrel, as by a free wheel clutch or the like device, is caused to directly or indirectly engage the driving shaft upon the rate of barrel rotation overtaking the rate of rotation of the driving shaft, the engine thereupon acting as a brake. In some cases the free wheel or like device connecting the barrel to the driving shaft may be such that the barrel and shaft 30 come into engagement when the barrel rotates at a predetermined speed less or greater than that of the shaft.

As the barrels of a multi-barrel winch embodying the invention are all similar it is sufficient to describe the invention in connection with one barrel only.

In the accompanying drawings Figure 1 shows, in central vertical section a winch barrel embodying the invention.

Fig. 2 is an end view of the winch barrel.

The barrel *a* is freely mounted on the driving shaft *b* and is driven in a hoisting direction through epicyclic gear comprising a brake drum *d* provided internally with a ring of teeth *e* engaged by planet pinions *f* secured to another adjacent brake drum *g*, it being understood that the barrel *a* is attached to the internally toothed drum *d* and that the driving shaft *b* has a

sun wheel *h* engaging the planet pinions *f*. The inner ends of the planet pinion spindles *i* are carried in a disk *j* mounted to rotate on the boss of the sun wheel *h*. The end of the barrel remote from the epicyclic gear drums is formed in one with or is fixed to another drum *m* that is also provided with a band brake and that has pivoted to it pawls *o* adapted to engage a ratchet wheel *p* fixed to the driving shaft *b* of the winch. The arrangement is such that, during hoisting, the barrel *a* and driving shaft *b* rotate in opposite directions and the pawls *o* slip idly over the ratchet wheel *p*, but during lowering, the barrel *a* and driving shaft *b* rotate in the same direction and the pawls *o* engage the teeth of the ratchet wheel *p* upon the rate of rotation of the drum *a* overtaking that of the driving shaft *b*, the engine, which in the case of an electric winch may be a shunt-wound motor, then acting as a brake. By these means the work usually taken by the ordinary brakes is or can be much reduced with corresponding prevention of overheating. The pawls may if desired be constructed and arranged so that they may be put out of action at will.

In the case of an electrically driven winch the connection of the barrel *a* to the shaft *b* when lowering may result in the motor being caused to generate electricity which may be utilized in the system with economical results.

Annular faces 7 on the adjacent faces of the brake drums *d* and *g* are adapted to be brought into frictional engagement by sliding the drum *g* toward the drum *d* by operation of a forked lever *g*¹ and sliding collar *g*² for the purpose of overhauling. When so engaged with each other, the two drums will revolve together if the brake bands of both drums be released, the drum *d*, which normally rotates in a direction opposite to that of the shaft *b* when the drum *g* is stationary, being then driven in the reverse direction.

As will be understood details of construction of the improved winch may be varied without departure from the invention.

What I claim is:

1. In a winch; a driving shaft rotated in one direction only, a hoisting barrel, adapted to rotate freely on said shaft in a lowering direction, and means for automatically

engaging said barrel with said shaft when said barrel rotates in a lowering direction at the desired limit of speed.

2. In a winch, a driving shaft, a hoisting barrel, adapted to rotate freely on said shaft in a lowering direction, and a ratchet device for connecting said barrel to said shaft when said barrel rotates in a lowering direction at a speed corresponding to that of said shaft.

3. In a winch, a driving shaft, a hoisting barrel freely mounted on said shaft, epicyclic gearing whereby said barrel is driven by said shaft, and means for automatically connecting said barrel to said shaft when said barrel rotates in a lowering direction at a speed corresponding to that of said shaft.

4. In a winch, a driving shaft, a hoisting barrel freely mounted on said shaft, epicyclic gearing whereby said barrel is driven by said shaft, pawls pivoted to said barrel, and a ratchet wheel fixed to said shaft and adapted to be engaged by said pawls.

5. In a winch, a driving shaft, a hoisting barrel freely mounted on said shaft, a brake drum having an internal ring of teeth fixed to one end of said barrel, a plain brake drum

fixed to the other end of said barrel, a sun wheel fixed to said shaft, planet pinions 30 gearing into said sun wheel and into the ring of teeth of said internally toothed drum, a brake drum carrying said pinions, pawls pivoted to said plain brake drum, and a ratchet wheel fixed to said shaft and 35 adapted to be engaged by said pawls.

6. In a winch, a driving shaft, a hoisting barrel freely mounted on said shaft, a brake drum having an internal ring of teeth fixed to one end of said barrel, a plain brake drum 40 fixed to the other end of said barrel, a sun wheel fixed to said shaft, planet pinions gearing into said sun wheel and into the ring of teeth of said internally toothed drum, a brake drum carrying said pinions, 45 means for moving said pinion carrying brake drum into frictional engagement with said brake drum having an internal ring of teeth, pawls pivoted to said plain brake drum, and a ratchet wheel fixed to said 50 shaft and adapted to be engaged by said pawls.

Signed at London, England, this 8th day of March 1917.

GEORGE THOMAS MACFARLANE.
